UNITED STATES PATENT OFFICE

ARTHUR F. POOLE, OF PELHAM MANOR, NEW YORK, ASSIGNOR TO REMINGTON ACCOUNTING MACHINE CORPORATION, OF NEW YORK, N. Y., A CORPORATION OF NEW YORK

COMPUTING MACHINE

Application filed May 1, 1923. Serial No. 635,847.

My invention relates to computing machines and it has for its principal object to provide certain improvements in function or symbol computing mechanism of the general 5 character set forth in my application for Letters Patent filed November 17, 1921, Serial No. 515,887, now Patent No. 1,528,567, dated March 3, 1925. In many respects the present invention may be regarded as an improvement 10 on that set forth in said application.

Another object of the invention is to provide certain locking devices and other improvements in computing mechanism.

To the above and other ends my invention 15 consists in certain features of construction and combinations and arrangements of parts, all of which will be fully set forth herein and particularly pointed out in the claims.

One embodiment of my invention is illustrated in the accompanying drawings, in which

Figure 1 is a partial front view, fragmentary in its character.

Figure 2 is a similar view on a smaller 25 scale but showing more of the machine.

Figure 3 is an enlarged side elevation of one of the symbol computing registers taken in section just inside the right-hand side plate, together with some of the associated 30 mechanism.

Figure 4 is a rear elevation of the symbol computing register with some parts broken away and some omitted.

Figure 5 is a partial front view of the interior mechanism of the register in section on the line 5, 5 of Figure 3.

Figure 6 is a partial sectional view of the upper part of the register, the section being 40 taken on the line 6, 6 of Figure 5.

Figure 7 is a developed diagram of the gearing in the register.

Figure 8 is a fragmentary operating view, in side elevation, of certain parts of the 45 mechanism of the register, said parts shown operated by the master dog of the machine.

Figure 9 is a partial plan view of the interior of the register, some parts being in section about on the line 9, 9 of Figure 5.

Figure 10 is a fragmentary right-hand end

elevation of a part of the machine showing certain locking mechanism.

Figure 11 is a plan view of a portion of said mechanism, partly in section on the line 11, 11 of Figure 10.

55

Figure 12 is a perspective view of a portion of the locking mechanism.

Figure 13 is a detail view of a certain lever in section centrally of a lever arm.

The present invention like that of my prior

patent aforesaid, is shown for illustration applied to the combined typewriting and computing machine shown in the patent to Wahl No. 1,270,471, dated June 25, 1918, to which patent reference is made for the general construction and mode of operation of the machine. Said machine has been manufactured for a number of years and is well-known in the art as the Remington accounting machine. Said machine consists essentially of a Remington typewriter having attached thereto the computing mechanism described in said Wahl patent. Said typewriter has a cylindrical platen conventionally indicated in Fig. 2 at 15 and it also includes the usual numeral keys and usually also letter and other keys, and operated by said keys in addition to the type bars of the writing machine is the usual Wahl calculating or computing mechanism which comprises among other things a master wheel 16, Fig. 3, and master dog 17, these constituting parts of the actuator of the Wahl mechanism. The main frame piece of said actuator is a casting 18 which, as described in the aforesaid

Wahl patent, is suitably mounted on the top plate of the typewriting machine. This casting has secured thereto in one way or another several vertical forwardly projecting frame plates including a plate 20 at the extreme

right-hand end of the machine, a second plate 21, Fig. 1, and other plates 22, one of which shows in Fig. 3. A truck 23 is connected at each of its ends by a bracket 24,

screw 25 and bracket 26, with the typewriter carriage so as to travel right and left therewith, said bracket 26 being rigidly secured to

said typewriter carriage. This truck is guided at the middle of the machine by certain rollers 27 of which one is shown in Fig.

95

100

10 mounted on a bracket 28 integral with the frame bar 18. The wheel 27 is integral with an arbor having a nut 30 on its upper end. Said truck 23 has mounted on its lower edge 5 a rack bar 31 into which the horizontal arm of the master dog 17 is adapted to engage during the effective part of each key stroke.

Any desired number of totalizers or registers can be mounted on and adjusted suitably along the truck 23. In the present instance I have shown in Fig. 2 one "dummy" 10 32 and one totalizer or register 33, besides my symbol computing registers.

The Wahl mechanism also includes a cross totalizer 34 mounted on a cross truck 35, which truck travels to the extent of one computing zone by ball bearings on a stationary rail 36 secured to the frame plates 20 and 21. This totalizer is actuated by a cross master 20 wheel 37, Fig. 1, which has suitably associated therewith a master dog that engages a rack 38. The truck 35 is normally held in its extreme right-hand position by a returning spring 40 and it is adapted to be 25 drawn along toward the left by the vertical totalizers or dummies 32, 33 by means of a hook 41 pivoted at 42 to a bracket 43 of the cross truck 35. This hook is accompanied by a detent 44. The hook 41 and detent 44 co- 30 operate with certain lugs projecting from the right-hand frame plates of the dummies or totalizers.

Each of the master wheels 16 and 37 is capable independently of the other of turning 35 one way for addition and the other way for subtraction and of being disconnected so as not to turn, said wheels being controlled in this respect by various devices shown in the Wahl patent referred to, said devices including certain cams 45, Fig. 2, mounted on suitable ones of the vertical totalizers or dummies, said cams controlling a follower roller 46, and various connections therefrom.

The Wahl mechanism includes a number 45 of locking devices, a part of one of which is indicated in the drawing, this being a lever 47 pivoted at 48 to the frame plate 20 and normally inclined leftward by a spring 50. This lever is adapted to be moved rightward 50 by an adjustable stop piece 51 on the cross truck 35. It controls a sliding link bar 52 which is connected through certain mechanism with means for locking the universal bar of the computing mechanism and therefore the numeral keys of the machine under 55 certain conditions fully set forth in the Wahl patent. In the present case the illustration of this lever and link is intended as a conventional illustration of a lock for the numeral keys of the machine.

The Remington accounting machine partially shown in the drawings also includes clearance proof mechanism for the cross totalizer 34, the greater part of which is 60 constructed according to the invention disclosed

in my Patents, No. 1,483,679, dated Feb. 12, 1924, and No. 1,491,167, dated Apr. 22, 1924, the latter patent being for certain improvements on the former. This mechanism has been slightly modified as to some of its details in the present case, as will be herein-after pointed out, but in its main features it is essentially as shown in the later one of the two prior applications mentioned. Said clearance proof mechanism includes a pivoted device or finger 53 projecting upward from the upper rear right-hand corner of the totalizer 34 and capable of occupying a forward position and a rear position, said finger being connected by means shown in the prior 70 patents referred to, to a feeler comb so that when all of the register wheels of the cross totalizer stand at zero, said finger is free to move to its rear position, but when any one of said wheels is not at zero, said finger is forced to occupy its forward position. It is shown in the drawings in its rear position.

Portions of the clearance proof mechanism and also of certain other mechanism are mounted on a frame piece 54 secured, Figs. 1 and 2, to the frame bar 18 by the same two screws 55 which fasten the plate 20 to said bar. The frame piece 54 is stamped and formed of sheet metal and it has projecting forward therefrom a headed screw post 56, Fig. 10, on which is pivoted the hub 57 of a three-armed lever 58, which lever is normally drawn counterclockwise (Fig. 1) by a spring 60. The depending arm of said lever has a lug 61 which, when the lever is turned by said spring, is adapted to operate the locking lever 47 and lock the numeral keys. It can be moved to its unlocking position by a finger piece 62. It is normally held in its unlocking position by means of a latch lever 63 pivoted on a post 64 projecting from the frame plate 54, said latch lever having a shoulder adapted to engage an ear 65 bent off from the upstanding arm of the lever 58. Said latch lever is moved to its latching position by the spring 60, the left-hand end of which is connected thereto. This latch lever 63 is adapted to be tripped by the travel of the carriage by means to be herein-after described. It is so tripped at the end of that particular computing zone in which the cross totalizer is supposed to be cleared by setting its actuator for subtraction and writing on the paper the total indicated. If the total has been correctly copied it will have brought the cross totalizer to zero or clearance, in which event the finger 53 will be capable of assuming its rear position and will, on the immediately following jump-back of the cross truck 35, restore the locking lever 58 to its normal position. These parts are shown in the drawing at this stage of the operation; that is to say, a total has just been correctly copied from the cross footer which has thereby been cleared and the cross footer has jumped back 125

and the finger 53 has restored the lock lever 58. This it has done by running under the edge of a bar 66 rigidly mounted by means of posts 67 on the leftward extending horizontal arm of the lever 58, said bar 66 having its left-hand end made on a bevel as shown. When the latch lever 63 was tripped and the lock lever 58 moved to its locking position, this leftward arm of said lever dropped downward and was immediately cammed up again by the finger 53 running under it on the jump-back of the cross footer.

In this jump-back operation the finger 53 was guided to its rear position by a cam 68, Figs. 10 and 12, consisting of a flange bent rearward from a depending part of a lever 70, which lever is pivoted on a vertical pivot 71 to a horizontal shelf 72 bent off from the bar 66. The lever 70 is normally impelled toward the rear by a spring 73 connecting it with an ear of the bar 66. The whole construction, as more fully explained in my Patent No. 1,491,167, is such that if the cross totalizer is clear on the jump-back, the cam 68 will draw the finger 53 rearward underneath the bar 66, which bar will be restored as described; but if the cross totalizer be not clear at the time, the finger 53 will be unable to move toward the rear and the lever 70 will therefore be forced to yield toward the front of the machine against the tension of the spring 73. Under these conditions the finger 53 will not move under the bar 66 but will pass in front of it, leaving said bar and the balance of the lever 58 in locking position, thus indicating to the operator that the total was incorrectly copied.

The machine is shown in the drawings set up for posting a loose leaf bank ledger, one sheet, 74, of which is indicated in Fig. 2 mounted on the platen 15 of the typewriter. The sheet is ruled in four columns respectively designated for "Deposits", "Checks", "Balance", and "Pick-up balance". Mounted on the truck 23 are a dummy 32 corresponding to the "Deposit" column; a totalizer or register 33 for the "Check" column; one of my symbol computers 75 for the "Balance" column; and a second symbol computer 76 for the "Pick-up balance" column. The method of posting such a ledger sheet is as follows: When the sheet is put into the machine the last item on it is the balance previously written in the third column. This balance is copied into the fourth or "Pick-up balance" column, the act of copying it causing it to be added in the cross totalizer 34. The carriage is then drawn back toward the right and line spaced and any deposits and checks required to be entered on that particular day in this particular account are written in their respective columns, the amounts of the deposits being automatically added in the cross totalizer and the amounts of the checks subtracted. The new balance will

then be shown on the cross totalizer 34 and will be copied in the third column, said cross totalizer meanwhile being automatically set for subtraction, with the result that the copying of the balance clears said cross totalizer. The particular function performed in this operation by my symbol computers has to do with the fact that the correctness of the work on these ledger sheets depends among other things on the correct writing of the pick-up balance, which if it be not correctly copied from the third column will of course introduce an error into the new balance and into the books generally. As the operator has to perform this copying operation every time one of these sheets is put into the machine, it will be seen that chances for error due to this cause are very great, and this has been in the past one of the greatest drawbacks to this ledger system. As has been explained in my patent above referred to, it is the purpose of these symbol computers as applied to this particular piece of work to give mechanical indication of any error made in copying the old balance from the paper. To this end when the newly computed balance is first written in the third column, a function or symbol of the number, or of the digits of the number, is computed in the register 75, said function or symbol consisting in the present instance of two digits M and N, Fig. 1, showing through suitable sight openings in said register. This symbol is written in the column 77 to the right of the balance, being copied there from the register, and the act of copying said symbol restores the symbol computing register 75 to zero. As will herein-after appear, means are provided to give a mechanical indication of any error made in copying this symbol from the register so as to assure that it be copied correctly. When in a subsequent operation on this particular ledger sheet this balance is copied in the fourth column, its symbol is likewise copied in a column 78. The act of copying the old balance in the fourth column automatically results in the computation in the symbol computing register 76 of the same symbol that was previously computed in the register 75. But the register wheels do not carry any numbers and the symbol cannot be read from the sight openings 80 of register 76 but must be copied from the column 77. As the mechanism of the two registers is substantially identical, the copying of the same identical balance in column 4 will compute the same symbol as was computed in column 3 and the writing of that symbol in column 78 will automatically restore register 76 to zero. Means are provided to give a mechanical indication at the proper time of failure of this register 76 to come to zero, and this will be an indication to the operator of an error in copying the number or its symbol from the paper, which error he can correct by comparing the figures 130

written in column 4 with the figures just to the left of them in column 3. In short, if the balance is not correctly copied from the third column of the paper, the machine will be locked up and the operator thus notified of his error.

The totalizer 33 is provided with a subtraction cam 45 which, acting on the follower 46, automatically sets the cross actuator for subtraction. The dummy 32 being unprovided with such a cam, numbers written in the first column will be added in the cross totalizer. The symbol register 75 is provided with a cam 81, the left-hand part of which, corresponding to the amount of the balance written in the third column, is of a level such as to set the cross totalizer for subtraction. The right-hand part 82 of this cam is of an intermediate level adapted to disconnect the cross totalizing mechanism so that the digits of the symbol written in column 77 will not affect the cross-master wheel 37, which will remain stationary while said digits are being written. The symbol computer 76 is provided with a cam 83, the left-hand part of which, corresponding to the amount of the pick-up balance, is at a level to cause addition in the cross totalizer; and the right-hand part 84 of which, corresponding to the symbol written in column 78, is of a level to disconnect the cross totalizing master wheel 37.

The symbol computing register 75 will now be described, reference being had to Figs. 3-9 inclusive. The framing of this register is similar in many respects to that of an ordinary Wahl totalizer comprising as it does two side plates 85 connected together by several cross bars and rods of which three, namely, 86, 87 and 88, in the lower front part of the register, are or may be exactly like corresponding parts of a Wahl totalizer, the bars 86 and 88 being mortised at their ends into the side plates 85 and the bar 87 mounted after the ordinary fashion of the Wahl totalizer. It is to the bar 88 that the cam 81 of register 75, and cam 83 of register 76 are secured. There is at the upper rear part of the register another cross bar 90 dove-tailed into the side plates in the same way as the similar bar in the Wahl totalizer, although this bar 90 has been modified in some other respects, as will appear hereinafter. The framing also includes a cross shaft 91 on which are journaled a series of thirty-toothed gears 92, said rod and gears occupying the same position as the corresponding parts of the Wahl totalizer, although the gears themselves are not provided with the transfer devices of the Wahl mechanism. The register also includes the two frame rods 93 and 94 in the lower back part of the register, these corresponding in position, and the lower one, 94, to a certain extent in function to rods in the ordinary Wahl totalizer. The side plates

are at their rear of dove-tail outline to provide for mounting on the truck 23 in precisely the same way as a Wahl totalizer. The register is also capable of being adjusted and secured in adjusted position on the truck in a way much like that of the Wahl totalizer; that is to say, said register is provided with a rock shaft 95 from which a finger piece 96 projects upward and forward through the casing plate 97. This shaft has rigidly mounted thereon two hooks 98 adapted to be caught over the dove-tail part of the truck 23 against which they are firmly pressed by a spring 100. One of these hooks 98 has a tooth 101 which is adapted to enter the interdental spaces of a rack bar 102 fixed to the truck 23 to hold the register in exact adjusted position along said truck. These parts do not differ at all in principle and but little in details from the corresponding parts of a Wahl totalizer except that the locking tooth 101 and finger piece 96, instead of being at the extreme right-hand side, as in the Wahl construction, are a little to the left thereof, this being to avoid interference with parts of the register mechanism.

The frame rod or shaft 91 has reduced ends that pass part-way through the frame plates 85 to which they are secured by screws 104, Fig. 5. The thirty-toothed gears 92 are plain spur gears, as shown in Figs. 3 and 5, being strung along the shaft 91 and suitably spaced as by washers 105. For reasons which will hereinafter appear, there is one of these gears not only for each significant letter space position of the numbers to be written but also the punctuation points are preferably provided with these gears. Otherwise expressed, there is a gear 92 for each letter space of the "Balance" column, irrespective of whether or not the numbers as actually written are spaced for punctuation. As indicated in Fig. 2, preferably a letter space position is left between the last digit of the balance and the first or M digit of the symbol, and this punctuation point is covered by the left-hand half of a gear wheel 92a, Fig. 5, of double width, the left half of the gear corresponding to the space, and the right half being turned by the master wheel 16 when writing the first or M digit of the symbol. The last gear 92 at the right, Fig. 5, is turned by the master wheel when writing the second or N digit of the symbol.

Each of the gears 92 is geared to one of four pinion shafts 106, 107, 108 and 109, Figs. 3 and 7. Each of these shafts extends across the register and has reduced ends journaled in side plates 85, as shown in Fig. 5, which represents the shaft 108 in longitudinal section. Each of these shafts has a series of pinions on it and as here shown each of them may be made by suitably turning down a piece of pinion wire, leaving pinions projecting where required.

Figure 7 is a developed diagram of the gearing, the right and left location of the several gears 92 being indicated by broken lines. From this diagram it will be seen that the shafts 106 and 107 are geared together to turn in opposite directions by thin pinions 110 at their left ends, these pinions not meshing with any gear 92. Also the shafts 108 and 109 are similarly geared together by a thin pinion 111 on shaft 109 meshing with a wide pinion 112 on shaft 108, said pinion 112 being wide enough to mesh with the first or highest gear 92, as indicated in Fig. 7 and also in Fig. 5. These four shafts have distributed along and among them a number of pinions 113, one pinion for each gear 92 and one for the double gear 92^a.

A shaft or rod 114 is mounted in the upper part of the register by screws 104, the same as the shaft or rod 91, and this shaft 114 has journaled thereon near its right-hand end two rotary devices 115 and 116, Fig. 9. The right-hand part of the device 115 consists of a gear 117, and the right-hand part of the device 116 consists of a gear 118, both of which gears show in Fig. 3, because in the particular design here shown, they do not happen to stand with their teeth in exact alignment. The gear 117 meshes with a pinion 120 of the first or M dial 121 on which the M digit of the symbol is computed and the gear 118 meshes with the pinion 122 of the right-hand or N dial 123 on which the N function is computed. These dials can be variously marked but in the present instance those of the register 75 are marked with the ten digits, 0-9 as usual. In fact, in the specific instance shown in the drawing, these are two ordinary Wahl register dials. Said dials are suitably journaled on a cross shaft 124 mounted at its ends in the frame plates 85, the dials being located and spaced by a collar 125 and washer 126. A collar 127 fixed to the shaft 114 prevents endwise motion of the devices 115 and 116.

As indicated in the diagram, Fig. 7, the gear 117 which drives the M dial 121 meshes with one of the pinions 113 on the shaft 107 so that this M dial is driven by the two shafts 106 and 107, in one direction by one of them and in the opposite direction by the other. The gear 118 meshes with one of the pinions 113 on the shaft 108 so that the end dial is driven by the shafts 108 and 109, in one direction by one of said shafts and in the opposite direction by the other. The gearing is such that when the master wheel 16 meshes with a gear 92 which is directly geared to the shaft 107, the M dial 121 will be turned in the same direction as the master wheel; and when said master wheel meshes with a gear 92 which directly drives the shaft 106, said M dial will be driven in a direction the opposite of that of the master wheel. Similarly when said master wheel engages a gear 92 which is geared directly to the shaft 108, the N dial

123 will be turned in the same direction as the master wheel and if said master wheel be geared to the shaft 109, then the N dial 123 will turn in the opposite direction from that of the master wheel. The digits are so arranged on the dials 121 and 123 that when the master wheel 16 is driven for addition, it has the effect on said dials of subtraction when the dials turn in the same direction as the master wheel and of addition when the dials turn in the opposite direction from the master wheel. In practice the master wheel 16 is driven additively when working on these symbol computers so that digits which directly turn the shafts 106 and 109 are added on the dials 121 and 123 respectively, and digits written when shafts 107 and 108 are directly actuated, are subtracted on said dials.

It will be understood that the gearing can be varied so as to compute different functions or symbols of the numbers written. The particular gearing hereinbefore partially described and hereinafter further described, is such that the first, third, fifth, etc. gears 92, beginning at the left of the series, 90 actuate the shafts 108 and 109 of the N train of gearing, and the even numbered wheels, the second, fourth, sixth, etc. actuate the forward shafts 106 and 107 of the M train of gearing, all as will be apparent from a little study of the diagram, Fig. 7. Furthermore of those wheels 92 which operate on the M train, the first works the shaft 108 and therefore acts subtractively on dial 123; the next works shaft 109 and therefore acts additively on dial 123, and so on, the successive digits that operate the N train acting subtractively and additively in alternation. A similar thing is true of the even numbered digits which act on the M train, the first of which, that is to say, the second digit of the number, operates the shaft 106 and therefore adds on the M dial 121; the next one, that is, the fourth digit, works the shaft 107 and therefore subtracts on the dial 121, 105 and so on. As has been said above, this scheme can be varied in many ways, and I have myself in a prior application, now Patent No. 1,519,328, dated Dec. 16, 1924, shown a symbol computer in which the symbols are 110 altogether different from those computed in the present instance.

In the diagram, Fig. 7, it will be noted that the third letter space from the right indicated by the broken line corresponding to the left half of the gear 92^a, does not contain any pinion 113 but the second space from the right, corresponding to the right-hand half of the wide gear 92^a, contains a pinion 113 on the shaft 107 so that when the M digit is written on the paper, it will be subtracted from the M dial 121, thus restoring that dial to zero. The right-hand gear 92 meshes with a pinion 113 on the shaft 108 and therefore turns the N dial 123 subtractively so that if 130

in this position of the carriage the N function be written, the N dial 123 will be restored to zero.

The M and N dials 121 and 123 have in 5 the present instance been constructed with ten spaces and their pinions 120 and 122 with ten teeth each, but there is no theoretical necessity for this particular number of spaces and teeth and in some registers of this general character I have used different numbers.

Ten teeth were adopted in the present instance because for certain reasons in this particular instance it was more convenient.

In order to hold the gear trains in normal 15 position when not being turned by the master wheel, it is sufficient to hold the two gears 117 and 118 because all of the other gears are geared to these, about half of the gears 92 being geared to 117 and the remainder to 20 gear 118. The means for thus holding the gear trains in proper position can be varied but as here shown it comprises two detents 128 and 130, each provided with a tooth 131, Fig. 3, normally engaging the gears 117 and 25 118. As best shown in Figs. 3, 5 and 8, these two detents are rigidly mounted as by pins 132 on a rock shaft 133 in the upper part of the register, said rock shaft being pivoted in the side plates 85. This shaft is shown 30 with two other arms 134 fixed thereon and projecting downward and rearward therefrom and in these two arms and in prolongations of one or both of the detents 128 and 130 there is inserted a wire 135 constituting a universal bar for certain key operated devices presently to be described. A spring 136 is stretched between one of these arms and a hook piece 137, Figs. 3 and 9, strung on shafts 114 and 124 and secured against 40 endwise motion by collars 138 on one of said shafts, said spring normally holding the detents 128 and 130 in operative position, from which they can be lifted as shown in Fig. 8.

In order to operate universal bar 135 at 45 each key depression, a series of levers 140 is provided, the upper ends of which lie in front of said universal bar, and which levers are pivoted on the frame rod 94 in much the same manner as certain levers connected with 50 the transfer mechanism of the Wahl totalizer. Said levers 140 are held in normal position by springs 141 connected to a cross rod 142 in the same manner as in the Wahl totalizer. These levers project below the 55 register in position to be operated by the master dog 17 in precisely the same way as the transfer levers of a Wahl totalizer, and some of them may be made longer than others, as indicated at 143 in Figs. 3 and 4. These 60 prolongations 143 are situated one just at the right of each space in which it is desired that the keys be locked. In the present instance there are two of them, one on the extreme left-hand lever 140, and one on that 65 lever 140 just to the right of the sub-unit's

space. These prolongations act in the same way as in the Wahl machine; that is to say, they are adapted to be operated by a short portion 144, Fig. 3, of the master dog 17, and are adapted to be arrested by a cross bar 145 on the actuator the same as in the Wahl machine, said cross bar having in it just back of the master wheel a notch into which the lower ends of the levers 140 can move when operated by the long tooth of the master dog. In this way the keys cannot be operated in the two positions mentioned. It may be added that the cross totalizer shown in Fig. 1 has no punctuation except the decimal point but that if it had spaces for commas, or if it were spaced for British money, for example, the keys would be locked at those spaces by the master dog of the cross footer. It will be understood that in the first part of the down stroke of a key the master dog 17 rocks to the position shown in Fig. 8, whereupon that particular lever 140 which happens to be in register with it will operate the universal bar 135, as shown in said figure and release the wheels 117 and 118 as shown. During the next part of the down stroke of the key the master wheel 16 is turned to operate the computing mechanism and at the last part of the down stroke the master dog returns to normal position, allowing the detents 128 and 130 again to lock the gearing.

It will be perceived from the description just above that at each key depression both trains of gearing are released from the dogs 128 and 130 but only one train of gearing is in mesh with the master wheel, and the other train is therefore free, so far as the detents are concerned. Said other train is however ordinarily locked by an aligning device 146, Fig. 3, which is part of the Wahl actuator. This is a stationary blade occupying the position shown in Fig. 3, and it is used to line up the thirty-toothed gears as they pass successively across it in the stepping of the carriage towards the left, this blade always engaging that wheel 92 immediately at the right of the one in engagement with the master wheel 16. It will be recalled that when the master wheel is in engagement with one of the gears 92 the one next to the right of it and locked by this blade 146, is a member of the other train of gearing so that when one train of gearing is connected with the master wheel the other is locked by this blade. This is one reason for having gears 92 in the punctuation spaces. Another reason is that except for the wide gear 92^a this register has a gear for every letter space position so that it will work equally well with all styles of punctuation in the cross totalizer 34. As to the gear 92^a itself the left-hand half of it is used exclusively for this locking purpose, it never being turned by the master wheel.

The method of locking just above described is however inapplicable when the last wheel

92 to the right is in engagement with the master wheel 16, and I have therefore provided a special lock for the M train of gearing at that time. To this end the last lever 140 at the right has pivoted thereto at 147, Figs. 3 and 8, a locking device 148 consisting of a bar extending toward the front of the machine and having in its forward end a horizontal slot 150 through which passes a reduced part of the shaft 106, the right-hand end of which is reduced as shown in Fig. 7. A spacing washer 151 may be placed on the shaft 106 between the device 148 and the right-hand side plate 85. This device 148 lies between the last gear 92 and the wide gear 92^a and it has bent off to the left from the lower part thereof a tooth 152 which registers with an interdental space of said gear 92^a. The construction is such that when the carriage stands in the position shown in Fig. 1, that is to say, in position for writing the N digit of the symbol, and a key is depressed to write such digit, the lever 140 being operated as shown in Fig. 8, draws the tooth 152 into locking engagement with the gear 92^a, thus locking the M train of gearing.

From a little consideration of the general scheme of the invention, it will be apparent that the symbol computing register when correctly operated, is normally clear, that its dials are displaced from their normal zero positions as soon as the operator begins to write the balance, and that they are returned to zero position by the act of writing the symbol. In order to give a mechanical indication of clearance or non-clearance of these dials, various devices may be employed and to provide improved devices for this purpose is one of the objects of the present invention. To this end each of the gears 117 and 118 preferably has a number of teeth equal to some multiple of the number of teeth in the pinions 120 and 122 of their respective dials, and in the present instance each of these gears has twenty teeth so that a half rotation of one of these gears corresponds to a full rotation of the associated dial. Each of the rotary devices 115 and 116, of which the gears 117 and 118 are parts, has as its left-hand part a flange 153, best shown in Figs. 6 and 9, but also shown in broken lines in Figs. 3 and 8. These flanges are not indicated in the diagram, Fig. 7. They are integral respectively with the gears 117 and 118 and are spaced leftward therefrom. Each of these flanges has at diametrically opposite sides thereof two cut-outs 154, the flanges themselves and their cut-outs being adapted for co-operation with two feeler noses 155, said noses projecting from arms 156 pivoted on the shaft 133, as best shown in Figs. 5 and 6. These two arms 156 are made of a single piece of sheet metal comprising also a cross or bail piece 157, the whole device being of course made by bending an appropriately shaped piece of sheet metal back

upon itself. One of the arms 156 lies between the hubs of the two detents 128 and 130 which prevents motion of the device endwise of the shaft 133. It will be perceived that the whole device is pivoted on the shaft 133; that one of its noses 155 bears on the flange 153 of the gear 117, and the other nose on the corresponding flange of the gear 118; and that if either of these gears is displaced from zero position the corresponding nose 155 rides on the periphery of the flange as shown in Fig. 6 but that if both gears are in zero position the two noses can both enter notches 154, thus allowing the feeler device to drop forward from its non-clear position shown in Fig. 6 to its clear position shown in Fig. 3. As best shown in Figs. 5 and 6 the left-hand arm 156 of this feeler device has an open-ended slot 158 into which a pin 160 projects from an arm 161, which arm is fast on a rock shaft 162 pivoted at its ends in the side plates 85. A spring 163 connected at one end to a pin 164 projecting from the arm 161, and at its other end to a fixed part, presses the noses 155 against the flanges 153 and when either train of gearing is displaced from its zero position the feeler device is forced outward against the tension of this spring, such outward motion of the feeler rocking the arm 161 and shaft 162 clockwise in Figs. 3 and 6. Fast on the shaft 162 at its lefthand end is a finger 165 which extends upward through a slot in the cover plate 97, projecting a short distance above the register. Fast on the right-hand end of the shaft 162 is a second finger 166 which also extends upward through a slot in the cover plate 97 projecting above the totalizer to the same level as the finger 165. The construction is such that when both symbol computing dials show zero these fingers 165 and 166 occupy a forward position, shown in full lines in Fig. 3, and that when one or both of said dials is out of its zero position these fingers occupy a rear position shown in Fig. 6 and also in broken lines in Fig. 3. These fingers control certain locking mechanism which will be described hereinafter.

I have mounted on the main frame piece 18 of the actuator above and about the bracket 28 a sheet metal housing and framework 167 designated generally by the reference numeral 167. This can be variously constructed but as here shown it is all stamped and formed out of a single piece of sheet metal. As best indicated in Figs. 1 and 11, said housing comprises at its right and left ends a foot piece 168 which rests on the upper edge of the casting 18 to which it is secured by a screw 170. Beginning the description at the right-hand end, the metal is bent upward to form a right-hand end wall 171, thence horizontally to form a roof 172, thence downward to form the left-hand end wall 171 and thence horizontally to form the left-hand foot piece 168 which is secured to the casting 18 by another

screw 170. The back part of the roof portion 172 is bent first downward and then in the inclined form shown to make a rear wall 173, which preferably closely meets the end walls 171 so as to make an enclosed housing. The front projecting part of the roof 172 is also bent downward horizontally to make a front flange 174 on which may be placed vertical line 175 to serve as a pointer co-operating with the usual scale provided on the cover plate 97 of the symbol registers and the cover plates of the totalizers. The rear plate 173 is flared rearward at the bottom, as best shown in Fig. 10. As also best shown in Fig. 10 a bracket 176 is secured by rivets 177 to the roof part 172 from which it depends, said bracket also being shown in section in Fig. 11. This bracket and the rear part or wall 173 are perforated for the insertion of a pivot rod 178 on which are pivoted three yoke frames or bails as shown in Fig. 11, said bails nested together and spaced apart by washers. Inside of the innermost of the three bails a sleeve 180 is mounted on the rod 178 between the rear arm of said bail and the bracket 176 and said sleeve is secured to the rod by a set screw 181 which prevents endwise motion of the rod, so that the whole thing can be assembled by putting the bails and sleeve in place and inserting the rod from the rear, afterwards tightening the set screw 181.

The outermost one of the three nested bails is numbered 182 and it has its forward arm prolonged toward the right, and a lug 183 is riveted to the front face of the free end of said arm. This lug as best shown in Fig. 1 is of V-shape, the point being downward, and it lies in the path of the fingers 165 and 166 when said fingers occupy their rear positions, indicating that the symbol computing register is not clear; but when said register is clear, said fingers pass in front of and do not engage said lug. The situation of this lug with respect to right and left is such that in case the symbol computing register is not clear, said lug will be cammed upward by the finger 165 as the register 75 enters a computing zone in its motion toward the left, or leaves a computing zone in its motion towards the right, and that the finger 166 will raise said lug as the register moves out of a computing zone toward the left or into one toward the right. As shown in Fig. 11, the finger 165 is just to the right of the left-hand frame plate 85. The finger 166 is bent off so as to bring its upper end just to the right of the right-hand frame plate 85. The whole construction is such that the lug 183 is operated whenever the register either enters or leaves a computing zone in either direction if said register is not clear, but is not affected if the register is clear.

The rear branch of the bail 182 is made into a depending arm 184 which for the sake of clearance is bent off toward the rear as shown

in Fig. 10 and carries at its lower end a pivot pin to which is pivoted the left-hand end of a push bar 185, this being the rearmost one of three such push bars shown in the drawing, all of which pass through the guide slots in the end wall 171 of the housing 167 and extend toward the right. The bar 185 passes through a suitable hole in a bracket 186 bent off from the frame piece 54 hereinbefore described. The end of said bar stands in operative relation to the upper end of a latch lever 187 similar to and pivoted on the same post 64 as the latch lever 63 hereinbefore described. The lever 187 is of bell crank form and its horizontal arm has a shoulder which normally restrains motion of an ear 188 bent off from a lever 190, the hub of which is pivoted just back of the lever 58 on the post 56. Said lever 190 at its lower end has an ear 191 adapted to operate a branch 192 of the locking lever 47, said branch having been riveted at 193 to said lever 47 for this purpose. The lever 190 has another ear 194 shaped into a restoring key and said lever is operated by a spring 195 which connects its upper arm with a depending arm of the latch lever 187 the same as has already been described in connection with the spring 60. The whole construction is such that whenever the lug 183 is operated by the passage of the register 75 into or out of a computing zone at a time when said register is not clear, the bar 185 is momentarily moved toward the right, tripping the latch lever 187, thus allowing the spring 195 to operate the lever 190 and locking lever 47, and thus locking up the machine. It will be understood that when the machine is correctly operated the register 75 never either enters or leaves a computing zone except in a clear condition, and if it ever does either of those things when it is not clear, the machine is locked up to notify the operator that a mistake has been made. The operator having been thus notified can instantly unlock the machine by a tap of the finger on the key 194. The key 194 and the key 62 both lie just to the right of the frame plate 20, and they are preferably adjacent to each other so that both can be struck by one blow of the finger, the two locking means being so related that it is never necessary to release one of them and to leave the other locked.

The innermost one of the three bails mounted on the rod 178, said bail being here numbered 196, has for its function the operation of the trip lever 63, which as has already been described is a part of the clearance proof mechanism for the cross totalizer 34. The forward branch of this bail is prolonged horizontally toward the right, as shown in Fig. 11, and as best shown in Figs. 1 and 11, it has a trip dog 197 pivoted thereto on a pivot pin 198. Said trip dog projects above the bail arm 196 and it has inserted therein a pin 200 having an enlarged head adapted by rest-

ing on the upper edge of the arm 196 to limit motion of the dog about its pivot in clockwise direction, as viewed in Fig. 1. The dog is turned in that direction by a spring 201 attached to said pin 200 and to the free end of the bail arm 196. Said dog projects below its pivot where it terminates in a sort of tooth having its left-hand edge abrupt and its right-hand edge inclined, as shown in Fig. 1.

As shown, for example, in Figs. 3, 4 and 11, the frame bar 90 of the register 75 has a rearward projection having a cam-shaped flange 202 projecting upward from its rear end; and projecting rearward from a portion of this cam flange is a lug 203, which lug is abrupt on its right-hand face and inclined on its left-hand face. The depending arm of the dog 197 lies in the path of this lug 203. The construction is such that when said lug engages said dog by the motion of the carriage toward the right, the dog is turned idly about its pivot against the spring 201 without operating the bail 196; but when said lug passes said dog in the leftward travel of the carriage, the inclined faces of the lug and dog engage each other, the dog cannot turn in clockwise direction and consequently the arm of the bail is raised upward momentarily and then allowed to drop.

The rear branch of the bail 196 is made with a depending lever arm 204, Fig. 10, which arm is articulated by means of a pivot pin 205 with the forwardmost one 206 of the three push bars which pass horizontally through slots 35 in the right-hand wall 171 of the housing 167. This bar 206, Fig. 12, passes through a hole in the bracket 186 and its end is in operative relation to the upstanding arm of the trip lever 63. The relation of the parts is such that the bail 196 is operated to trip the latch 63 in that step of the carriage immediately following the writing of the last digit of the balance in the third column on the ledger sheet. The next following operation of the machine is to strike the space key and allow the carriage to step into column 77 to write the first or M digit of the symbol. As will appear hereinafter, the hook 41 is cammed loose from the register 75 during the same step 50 of the carriage above mentioned; that is to say, the one immediately following the writing of the last digit of the balance. The whole construction then is such that at that step of the carriage, which is the instant when the cross totalizer should be cleared, the locking lever 58 is operated, the cross totalizer takes its jump toward the right, and if said totalizer is clear as it should be, it will immediately restore said locking lever to normal position. 55 If, on the contrary, a mistake has been made and the cross totalizer is not clear, the machine will be locked and the operator will be unable to write the symbol, thus calling his attention to the error. He can then unlock 60 the machine by a tap on the finger piece 62

and proceed to make the necessary correction.

It has been found in practice desirable to effect a fairly nice relation between the trip levers 63 and 187 on the one hand, and their push bars 206 and 185 on the other, and I have devised improved means for this purpose, which means are extremely simple and convenient in practice. The upper end of each of said trip levers 63 and 187 has been folded back on itself and a tapped hole made through the lever thus doubled in thickness into which is screwed an adjusting screw 207. The hole being drilled through the slit between the two holes of the metal, said metal springs a little under the action of the tap by which the screw threads are made so that the hole when the tap is removed is a little smaller than the tap; and when the screw 207 is screwed into said hole, the metal is forced apart a little so that said screw is under stiff spring pressure which, while not preventing it from being turned with a screw driver, does prevent it from jarring loose and changing the adjustment. A hole 208 in the right-hand branch of the frame plate 54 is provided for the insertion of a screw driver by which these screws can be readily adjusted, and they will maintain their adjustment without further thought or attention.

As shown in my patents, Nos. 1,483,679 and 1,491,167, the clearance proof mechanism for the cross footer included a locking lever corresponding to the lever 58 of the present case, a trip lever corresponding to the lever 63, and devices for tripping said trip lever at the middle of the machine including a tappet on the appropriate one of the vertical totalizers. On account of the bracket 28 these trip devices were off-set to the right of said bracket, and this necessitated making the trip device on the totalizer in the form of a bar projecting to the right of one totalizer and extending if necessary over the top of another totalizer. This construction has been improved in the present case by the device of employing bails mounted as described on the pin 178, thus bringing the parts to be operated around in front of said bracket 28 and enabling the co-operating parts mounted on the registers 75 and 76 to be located within the bounds and 100 usually near the middle of the register.

In the ordinary Remington accounting machine, and as fully described in the Wahl Patent 1,270,471, the hook 41, which controls the cross truck 35, is picked up by a lug 105 projecting from the right-hand frame plate of each vertical totalizer; and in that step of the carriage immediately following the writing of the last digit in a computing zone, said hook is cammed downward out of engagement with said lug and the cross truck is jumped back to its right-hand position by its returning spring 40. In the case of the register 75 it is desired that the same operation shall take place but obviously this could 110 115 120 125 130

not be done by making the lug on the right-hand frame plate 85. A suitable lug for the purpose can be constructed in various ways. As here shown advantage is taken of the fact that no lever 140 occupies the sub-unit's place on the rod 94 and accordingly a special piece 210 is mounted on said bar as shown in rear view in Fig. 4 and in side elevation in Fig. 3. This piece has a hub which fits tightly on the bar and it projects upward enough so as to have in its upper end an open ended crotch or fork which embraces the frame rod 93 to prevent rotation about the rod 94. This piece is extended downward, its lower end constituting a lug 211 in position to catch the hook 41. In order to space this piece and lug exactly in a right and left direction without careful adjustment and to maintain it accurately spaced, an arm 212 is bent off from the piece 210 toward the right, its right-hand end abutting the right-hand frame plate 85, as shown in Figs. 1 and 4.

If when the cross truck is freed from the lug 211 it jumped clear back to its normal position, its stop piece 51 would strike the locking lever 47 and lock up the machine so that the symbol could not be written. In order to prevent this I have provided improved means which will now be described. Of the three bails which are mounted on the rod 178 at the middle of the machine, the middle one 213 has its forward arm extended toward the right and provided at its under edge with a rounded nose adapted to ride on the cam 202 hereinbefore referred to. This cam has inclined ends and a horizontal dwell of several letter spaces extent, and it is so positioned and related to said nose as that said nose is cammed upward by it and is held in its upper position not only during that step of the carriage immediately following the writing of the last digit of the balance but also during those steps of the carriage employed in writing the two digits of the symbol. The rear branch of this bail has a depending arm 214 which is articulated with the middle one 215 of the three bars which pass through slots in the right-hand wall 171 of the housing 167. This bar 215 is shorter than the other two and is so shaped that its right-hand end is on a lower level than they, its said end being pivoted at 216 to a lever arm 217 which is pivoted on a pin 218 projecting forward from the frame piece 54. The arm 217 is one arm of a bell crank, the other arm 220 of which extends toward the right and has a headed pin 221 projecting into a slot 222 in a vertical sliding piece 223. Said piece 223 has as viewed from the front of the machine the shape of an inverted T, its lower end having a cross bar 224. The stem of said T is at its lower end offset toward the front of the machine to bring the cross bar 224 into the vertical plane of the cross truck 35 for which it is adapted

to act as a stop. The bell crank 217, 220 is controlled by a spring 225 which normally holds the piece 223 in its upper position. Said piece 223 projects some distance above the arm 220 to which it is connected by an inclined tension spring 226, the tension of which tends to press the upper end of the slot 222 down against the pin 221 and also tends to rock the piece 223 counter-clockwise about said pin 221. This rocking tendency causes the right hand end of the cross bar 224 to rub against the right-hand side plate 20 of the machine frame, as shown in Fig. 1. This piece is shown in the drawings in its depressed position caused by the nose of the bail 213 riding on the cam 202 and in that position the left-hand end of the cross bar 224 serves as a stop to limit the right-hand jump of the cross truck and thus prevent it from operating the locking lever 47. The mechanism is shown in Fig. 1 in position for writing the second or N digit of the symbol and it will be seen that in the next step of the carriage following the writing of said digit the bail 213 will be released from the cam 202 and the piece 223 will be drawn upward by the spring 225, thus withdrawing the stop 224 from the path of the cross truck, and allowing said truck to move on to its extreme right-hand position. The slot 222 enables the lever 217, 220 to be operated without breakage of the parts in case the cross truck happened to be in its extreme right-hand position at the time, as it would be when the carriage is drawn back toward the right to begin a new line of writing. Rotation of the piece 223 about the pin 221 is prevented in one direction by the bar 224 pressing against the plate 20 and in the other direction it is prevented by a pin 228 projecting forward from the frame piece 54. Upward motion of the arm 220 is conveniently limited by the head of the pin 221 striking the head of the post 64, said heads being suitably flattened for the purpose. In order to arrest the return strokes of all of the bails 182, 196, and 213, a stop pin 199 is shown at the left of the rear depending arms of all of said bails.

In order to provide an adjustment in the train of connections from the bail 213, to the piece 223, the lever 217, 220 is made as shown, for example, in Figs. 12 and 13, the latter figure being a central section longitudinal of the arm 220. As here shown, said arm 220 is staked on a hub 230 which is directly pivoted on the pin 218 and the arm 217 has a hub 231 pivoted on the hub 230. Said arm 217 has two ears 232 bent forward therefrom and embracing the arm 220, which latter arm has a tongue 233 struck out therefrom between said ears. Adjusting screws 234 are screwed through the ears 232 and clamp the tongue 233 between them. These screws enable a relative adjustment to be

made between the arms 217 and 220 after which said arms act as the arms of a rigid bell crank.

In my patent No. 1,528,567, after the cross truck was cammed loose from its rigid hold on the symbol register, it was again caught by a second lug on the same register, but this arrangement gave the cross truck a shorter jump than was desirable in order to operate the clearance proof mechanism for the cross totalizer. The present arrangement, including the stop 224, enables me to get a longer jump better adapted for this purpose. In most cases it is more or less immaterial at precisely what point the cross totalizer be arrested, the only thing that requires care being that it be not arrested at a point where the cross computer master dog would be locked as, for example, in that latter space position just to the left of the first register wheel or on a punctuation point. In order to take care of this possibility it may be necessary in some instances to lengthen or shorten the bar 224 to the extent of a letter space or two. Usually if this trouble was encountered it could be overcome by removing $\frac{1}{16}$ of an inch of the bar 224 at its left end.

The symbol computing register 76 is provided with a cam 202 but not with the lug 203 as the cross totalizer is not intended to be clear at the time when the register 76 is in use.

In said register 76 the dials 121 and 123 are not provided with numerals and they may be entirely blank. To facilitate making the necessary correction in case one or both of these dials should ever get normally out of its zero position, it may be preferable to make each of them with its periphery of a uniform color, for example, red, and to make its zero position of a different color, for example, black, the latter being the color usually employed on the cover plate of the register. By this means these dials are inconspicuous except when out of their zero positions. If one of them got misplaced so that it required correction, this could be done by repeated operation of the "1" key until the black spot showed at the sight opening.

The use of my invention can be understood from the specific instance above described. When the balance is being written in the third column, its appropriate symbol is computed in the register 75 and copied in column 77 from said register, which is thereby restored to zero. When this particular ledger sheet is again put into the machine that balance is copied from the third column of the paper in the fourth or pick-up balance column on the paper and its symbol is copied from column 77 into column 78. If the copying has been correctly done all will go well but if not, when the register 76 steps out of the computing zone, its finger 166 will operate the lug 183 and cause the lever 190 to be tripped and to lock the machine. If by

any chance this register had been out of its normally clear condition at the time when the machine was brought into the column, the same locking up would have been accomplished by the finger 165 and the writing of the pick-up balance would have been prevented until the error should have been corrected. The operator is thus warned both in case the register was not in proper condition for use before writing the balance and also after it was written in case the balance had been incorrectly copied. In the machine shown in my patent No. 1,528,567, there was means to lock up the machine in case the symbol register was not clear but this means was not controlled by the travel of the carriage. On the contrary, the lock was of such character as to prevent the return stroke of the key when writing the last digit of the symbol. The present construction is preferable for several reasons, one of them being that it gives a warning before writing the balance in case the register is not clear, and also being operated by the travel of the carriage it works better.

In my prior patent aforesaid, there were no wheels such as the wheels 92 in the spaces set apart for punctuation and the lock including the tooth 152 which cooperates with the gear 92^a was not present. With those exceptions the general scheme of computing a symbol was substantially the same as in the present machine. My prior application also shows gear locking devices similar to the detents 128 and in a general way similarly operated and also feelers corresponding functionally with the feelers 156, 155 of the present case. These feelers, however, do not operate fingers like the fingers 165, 166 but operate the other lock referred to.

Various changes may be made in the details of construction and arrangement without departing from my invention.

What I claim as new and desire to secure by Letters Patent, is:—

1. In a computing machine, the combination with a carriage having an extent of travel equal to a plurality of computing zones, a register, and a master actuator, one of which travels with said carriage, of clearance proof mechanism for said register including means to notify the operator of the state of the register, and means actuated by the travel of the carriage for bringing said notifying means into operation on entering a computing zone and again on leaving a computing zone.

2. In a computing machine, the combination with a carriage having an extent of travel equal to a plurality of computing zones, a register and a master actuator, one of which travels with said carriage, of clearance proof mechanism for said register comprising two fingers, one at the left side and one at the right side of said register, and means actuated

- by said fingers for notifying the operator of the state of the register at the beginning and also at the end of a computing zone.
3. In a computing machine, the combination with a main carriage having an extent of travel equal to a plurality of computing zones, one or more registers for said plurality of computing zones, and a cross computing register, of a lock, means actuated by said cross computing register for operating said lock in case said cross computing register is not clear, and separate means actuated by the first mentioned register or one of said registers for operating the same lock in case that register is not clear.
4. In a computing machine, the combination with a main carriage and a register thereon, a jumping cross computer carriage or truck, of a stop for said cross computing truck, and means whereby said stop is moved to operative and inoperative position by the first mentioned register.
5. In a computing machine, a symbol computing register mounted on a traveling carriage and having therein two trains of gearing, means for operating said trains of gearing one at a time, and a lock thrown into one train of gearing by the actuation of the other train of gearing.
6. In a computing machine, the combination with a master wheel and master dog, of a symbol computing register comprising a plurality of gears operable by said master wheel, and means operated by said master dog for locking one gear while another gear is being operated.
7. In a computing machine, the combination of a main truck having one or more registers mounted thereon including a register of greater width than a computing zone, a cross truck, means whereby said registers one at a time pick up and release said cross truck, a stop for arresting the jump back of said cross truck, and means whereby said wide register moves said stop into the path of said cross truck.
8. In a computing machine, the combination with a traveling carriage and a jumping cross truck, of a stop for arresting the jump back of said cross truck, and means for moving said stop into operative position during a predetermined portion of the travel of said carriage.
9. In a computing machine, the combination of a lever, a push bar for operating said lever, and an adjustable abutment for regulating the action of said bar on said lever, said abutment consisting of an adjusting screw screwed through a hole between the two branches or layers of said lever made by folding the metal of the lever back on itself.
10. In a computing machine, the combination with a main carriage, a register or registers mounted thereon, a jumping cross truck, and a hook or coupler by which said cross truck is intermittently connected with said register or registers, of a piece in said register for picking up said hook or coupler, said piece consisting of a plate mounted on a rod in said register and having a lug for co-operation with said coupler and having also an arm bent off therefrom and contacting with a frame plate of the register to locate accurately said lug.
11. In a computing machine, the combination with a main carriage, a register thereon having a cam with a dwell, mechanism operated by said cam and held in operative position by said dwell through a predetermined portion of the carriage travel, a jumping cross truck, a stop thrown into the path of said cross truck by said mechanism, said mechanism including a yielding part to enable the mechanism to be operated without operating said stop in case the cross truck is in the way of an operation of said stop.
12. In a combined typewriting and computing machine, the combination with a traveling carriage having a plurality of registers for different columns and a cross totalizer, of clearance proof mechanism for said cross totalizer including trip devices operated by the travel of one of said vertical registers, said trip devices including a bail at the middle of the machine having its forward arm operated by a trip device on said register, and notifying devices operated by the rear arm of said bail.
13. In a combined typewriting and computing machine, the combination with registering mechanism and a traveling carriage, of indicating mechanism including one or more bails at the middle of the machine, trip devices on a register and acting on the forward arm or arms of said bail or bails and indicating devices controlled by the rear arms of said bails.
14. In a computing machine, the combination with a plurality of registers, of a plurality of clearance proof devices one for each register, and restoring keys for said clearance proof devices situated adjacent to each other so that both can be operated by one stroke of the operator's finger.
15. The combination with keys, a master wheel, and a universal member operated alike by all of said keys; of registering mechanism including a series of gears operable by said master wheel, and a lock thrown by said universal member into engagement with one of said gears while another of said gears is being actuated by said master wheel.
- Signed at the borough of Manhattan, city of New York, in the county of New York and State of New York, this 30th day of April A. D. 1923.
- ARTHUR F. POOLE.
